UNITED STATES PATENT OFFICE.

FRANK WINTERRATH, OF BROOKLYN, NEW YORK.

COMPOSITE MATERIAL.

1,369,151.

Specification of Letters Patent. Patented Feb. 22, 1921.

Application filed April 1, 1920. Serial No. 370,591.

To all whom it may concern:

Be it known that I, FRANK WINTERRATH, a citizen of the United States, and resident of the borough of Brooklyn, in Kings county 5 and State of New York, have invented certain new and useful Improvements in Composite Materials, of which the following is a description.

This invention relates to an improved 10 composite material, and has for its primary object to provide a simple and inexpensive material which will be impervious to air or moisture, and which can be advantageously employed for numerous purposes where a 15 material having the attributes of lightness, durability, cheapness and attractiveness are essential requisites.

In one embodiment of the present invention, which I have found to be admirably 20 adapted for the purpose of increasing the acoustic properties and the ornamental appearance of the walls of the sound amplifying horns or chambers of mechanical sound reproducing instruments, I provide a base 25 or backing sheet of heavy burlap or other textile material, upon which a body layer of plastic material of cementitious nature is applied. A facing sheet of muslin is then arranged upon the plastic body, and the 30 three layers of material are permanently secured to each other through the medium of a suitable adhesive. A finishing coat of enamel or celluloid paint is then applied to the facing sheet, preferably by spraying. 35 This finished surface may be given a very high polish, so that it will be absolutely smooth and unbroken. The surface coating of enamel or celluloid paint may be of any desired color, so as to enhance the ornamental 40 appearance of the phonograph or other article.

My invention also contemplates the provision of a composite material, as above characterized, which will not be deleteriously 45 affected by changes in temperature, and which, therefore, will not warp or lose its original form or shape.

With the above and other objects in view, the invention consists in the improved composite material to be presently described in detail, and subsequently pointed out in the subjoined claims, reference being had to the accompanying drawing, wherein I have 50 illustrated a practical embodiment of the invention, and in which similar reference char-

acters indicate corresponding parts throughout the several views.

In the drawings,

Figure 1 is a perspective view showing the three sheets or layers from which the 60 final manufactured product is produced, slightly separated from each other.

Fig. 2 is a sectional view through the completed product.

Fig. 3 is a perspective view of the product, 65 indicating the highly polished finished surface thereof, and,

Fig. 4 is a similar view showing the reverse or back surface of the composite material.

Referring in detail to the drawings, 70 5 designates the back sheet or layer of material which serves as a foundation for the intermediate body layer 6, of plastic cementitious material. The backing sheet 5 is preferably 75 of heavy burlap or other similar fabric, and upon one side of the burlap the plastic body layer 6 is disposed. This body layer is preferably of plaster composition of the requisite consistency, and is evenly spread over 80 the backing sheet of burlap. A glue or adhesive composition, indicated at 7, in Fig. 2 of the drawings, is then applied to the plastic body layer, and finally the face sheet 8, of muslin, is smoothly applied to the surface of the plastic body layer. The glue 85 composition causes the cementitious particles to be homogeneously united, and said body layer hardened and rendered perfectly rigid.

To the opposite side of the burlap backing sheet 5 a water-proof adhesive composition, indicated at 9, is also applied, said composition filling the interstices of the burlap, and uniting with the intermediate body 95 layer 6. In this manner there is produced what is practically a continuous one-piece rigid structure.

In accordance with the particular purpose for which the composition material is to be 100 used, the facing sheet of muslin may be coated with various preparations. Thus, after applying a sizing coat to the muslin face sheet, a finishing coat of enamel or celluloid paint, as indicated at 10, is uniformly distributed over such surface, preferably by spraying the paint. This surface is finally rubbed down and highly polished. The material thus finished may be advantageously utilized in the construction of the 110

walls of sound amplifying chambers or horns, such as are provided in mechanical sound reproducing instruments. It has been found that the highly finished and glazed 5 surface material enhances the volume of sound and the quality of the tone of the instrument, and in view of the fact that the composite material is absolutely impervious to moisture, it will not crack, warp or otherwise 10 become deformed from its original shape or condition. Furthermore, as the material may be finished in any desired color, the artistic appearance of the instrument will be greatly increased, and the selected 15 color may harmonize with the color scheme of the other appointments of the room or apartment in which the instrument is placed. It is obvious that in the above particulars the improved composition material 20 is superior to wood or metal heretofore utilized in the construction of such instruments.

I have above referred to one of the more important uses to which the improved composition material may be applied, but numerous other purposes for which the material might be advantageously employed will readily suggest themselves. Thus I have found that such material when used in the construction of the bodies and limbs of dolls is far superior to the use of wood or plastic composition materials. The latter are comparatively heavy, and will readily chip or break off in small particles, and are likewise 35 subject to deterioration when exposed to sudden changes in temperature, or to the action of moisture. My improved composition material, on the other hand, when manufactured into dolls, is remarkably light, 40 even in dolls of the largest size. It is also exceedingly strong, rigid and durable, and will not break, crack or chip, should the doll be abused or roughly handled.

In addition to the above, my improved 45 composition material may also be utilized as a wall board in the construction of walls and partitions, it, of course, being understood that in such case the body layer of plaster composition will be of the requisite 50 thickness, and the burlap backing sheet sufficiently heavy to afford the necessary strength and rigidity in the wall structure. Furthermore, the material can also be serviceably used as a veneer sheet for various 55 manufactured articles of wood, as it will take and retain a very high polish on its exposed surface.

Again, the present invention may be utilized by artists as a substitute for the customary canvas board with marked advantages owing to the fact that the composition material is non-absorbent and impervious 60

to moisture. Its finished surface will, therefore, readily hold the applied paint, and the possibility of cracking of the paint by the warping of the board is obviated.

From the foregoing description considered in connection with the accompanying drawing, the construction and several advantages of my improved composition material will be fully understood.

I have herein given several examples of practical applications of the new material, but it is, of course, apparent that this material may likewise be adapted to numerous other uses, and in such applications it may be necessary to slightly change the composition of the several superposed laminations constituting the completed product. Accordingly I reserve the privilege of adopting all such legitimate modifications as may be fairly embodied within the spirit and scope of the invention as claimed.

I claim:

1. A laminated composite material consisting of a relatively heavy textile backing sheet, a body layer of plastic material applied to one side of said backing sheet, a facing sheet of relatively fine textile material covering said plastic layer, and an adhesive permanently uniting the several superposed layers of material to each other.

2. A laminated composite material consisting of a relatively heavy textile backing sheet, a body layer of plastic material applied to one side of said backing sheet, a facing sheet of relatively fine textile material covering said plastic layer, an adhesive permanently uniting the several superposed layers of material to each other, and a composition finishing coat applied to said surface sheet, and capable of receiving and retaining a highly polished surface.

3. A laminated composite material consisting of a relatively heavy textile backing sheet, a body layer of plastic material applied to one side of said backing sheet, a facing sheet of relatively fine textile material covering said plastic layer, an adhesive permanently uniting the several superposed layers of material to each other, a waterproof adhesive composition on said textile backing sheet, and a composition finishing coat applied to said surface sheet, and capable of receiving and retaining a highly polished surface.

In testimony that I claim the foregoing as my invention, I have signed my name in presence of two subscribing witnesses.

FRANK WINTERRATH.
